UNITED STATES PATENT OFFICE.

RICHARD FRANCIS PEARCE, OF BLUNDELLSANDS, LIVERPOOL, ENGLAND.

APPARATUS FOR WASHING GASES.

1,200,974.

Specification of Letters Patent.

Patented Oct. 10, 1916.

Application filed June 3, 1916. Serial No. 101,521.

To all whom it may concern:

Be it known that I, RICHARD FRANCIS PEARCE, a subject of the King of Great Britain, residing at Rotheraslaide, Merrilocks 5 Road, Blundellsands, Liverpool, England, have invented new and useful Improvements in Apparatus for Washing Gases, of which the following is a specification.

This invention relates to that method of collecting fume, flue dust and other matter suspended in gas, wherein the gas enters 10 a receptacle or tank, containing water and a submerged filtering medium, through the wall of the said tank below the level of the water and the filter and rises up through 15 the water and through the filter, the fume being thereby separated from the gas and remaining in suspension in the water as described in the specification of former Letters Patent granted to me No. 1,028,487.

According to my invention instead of forcing the gas under pressure through the water and filtering material I make use of a fan or exhauster capable of maintaining a 20 partial vacuum in the container above the water level whereby the gas will be sucked through the filtering medium, the obstruction offered by the filter to the flow of the gases causing an automatic distribution of the gases over the whole area of the filter. 25 Further, as in practice the incoming gas forces the water out of the inlets into the tank it follows that the fume or flue dust is liable to deposit therein, and I therefore furnish the inlet pipes with devices by means of 30 which they can be freed from deposited fume from time to time as required.

My invention will be readily understood by reference to the accompanying drawing 35 which illustrates in sectional elevation an apparatus embodying my present improvements.

a indicates the tank and *b* the filtering medium mounted therein, and which, when 40 the apparatus is in use, is below the level of the water in the said tank.

c is one of the gas inlet pipes which is represented as being free from water as in the case when the gas is flowing through it, and 45 *d* one of the outlets, the said outlet being connected with a flue *e* from which the gas is designed to be exhausted by a fan or exhauster, and provided, as shown, with a

valve *f* by means of which it can be closed when desired.

Each of the inlet pipes *c* at the point of entry into the tank is made straight and furnished with an extension *g* closed by a cap *h*. In this extension is arranged a plunger *i*, the rod *k* of which passes through a stuffing box in the cap *h*, so that the said plunger can be reciprocated in order to discharge or push out from the inlet *c* any accumulation of condensed fumes.

To permit of reciprocating the plunger the latter is made tubular and internally screw-threaded, and in a cross head *l* carried on pillars *m*, *m* fixed to the cap *h*, is mounted a screw *n* which engages with the threads in the tubular rod *k* in such a manner that, 60 when the said screw *n* is rotated by means of a hand-wheel *o* the plunger *i* will be moved longitudinally in the outlet pipe *c*.

By constructing the inlet pipe *c* with an extension as described it will be seen, by 65 reference to the drawing, that normally the plunger *i* offers no obstruction to the free admission of the gas into the apparatus.

p is a gage for showing the height of the water in the tank and *q*, *q* are drain cocks 80 through which the water and fume can be discharged from time to time as required. As shown in the drawing the bottom of the apparatus is formed with inclines as at *r* so that any deposited fume may gravitate 85 toward the said drain cocks.

Having now fully described and ascertained my said invention and the manner in which it is to be performed, I declare that what I claim is:—

1. An apparatus for washing gases comprising a washing tank provided with a filtering screen and adapted to contain a cleaning fluid, an inlet pipe for the gases, connected to said tank beneath said screen and provided with a cleaning arm, a piston mounted in said cleaning arm and provided with a threaded stem, a screw carrying member secured to said arm, a screw mounted in said member and engaging the threads of 95 said stem for operating said piston, and a gas outlet pipe also connected to said tank.

2. An apparatus for washing gases comprising a washing tank provided with a filtering screen and adapted to contain a cleaning fluid, an inlet pipe for the gases connect- 100 105

ed to said tank beneath said screen and provided with a cleaning arm, a yoke shaped member carried by said arm, a piston mounted in said arm and provided with a hollow 5 internally threaded stem, a screw rotatably mounted in said yoke shaped member and engaging the threads of said stem for op-

erating said piston, and a gas outlet pipe connected to said tank for withdrawing the gases from the same.

RICHARD FRANCIS PEARCE.
